CLAIM

The ornamental design for a leg press machine as shown and described.

DESCRIPTION

FIG. 1 is a top, front, right side perspective view of a leg press machine showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partially enlarged view thereof, taken from FIG. 1;

FIG. 10 is a partially enlarged view thereof, taken from FIG. 7; and,

FIG. 11 is a partially enlarged view thereof, taken from FIG. 5.

The broken lines in the figures illustrate the portions of the leg press machine and form no part of the claimed design. The dot-dash broken lines of FIGS. 1, 5, 7, 9-11 are included to show partially enlarged views only and form no part of the claimed design.
